REAMER BODY

Otto Hammer, Whittier, Calif., assignor to Security Engineering Co., Inc., Whittier, Calif., a corporation of California

Application September 22, 1937, Serial No. 165,148

11 Claims. (Cl. 255—73)

This invention relates to improvements in well reamers, and particularly to the bodies for such well reamers.

Heretofore, a highly successful reamer has been developed having a structure similar to that disclosed in Reissue Letters Patent No. 19,339 issued to John A. Vertson. In such constructions a steel reamer body is provided which is incorporated in the drill string, this reamer body carrying rotatable cutters which are rotatable about laterally inclined axes when viewed in front elevation. The construction of these reamer bodies is somewhat expensive and sometimes difficulty is encountered in incorporating these reamer bodies at the desired position in the drill string.

It is an object of the present invention to provide an improved reamer body which may or may not incorporate the reamer design as disclosed in the Vertson patent, and which can be clamped at any desired location around the drill pipe. In this way the cost of the reamer body may be materially reduced and the reamer may be positioned wherever desired.

It is another object of the invention to provide an improved reamer construction wherein the body of the reamer is formed of two opposed parts adapted to be positioned in encircling relation around the drill pipe, two adjacent sides of the parts being hingedly connected by a cutter pin so that the cutter pin serves two functions, namely to hinge the parts together and to provide an axis about which its replaceable cutter may rotate.

A further object of the invention is to provide novel, simple, and durable means for so mounting the reamer body on a drill pipe as to prevent rotation of the reamer body relative to the drill pipe during reaming.

With the foregoing and other objects in view which will be made manifest in the following detailed description and specifically pointed out in the appended claims, reference is had to the accompanying drawing for an illustrative embodiment of the invention, wherein:

Figure 1 is a view in front elevation of the improved reamer embodying my invention;

Fig. 2 is a view in rear elevation of the improved reamer embodying the invention;

Fig. 3 is a horizontal section taken substantially upon the line 3—3 upon Fig. 1;

Fig. 4 is a partial view in vertical section taken substantially upon the line 4—4 upon Fig. 3, illustrating the means of holding the reamer body against rotation relative to the drill pipe;

Fig. 5 is a view in vertical section illustrating

an alternative means for holding the reamer body against rotation upon a drill pipe; and

Fig. 6 is a partial view in vertical section illustrating another means for holding the reamer body against rotation relative to the drill pipe.

Referring to the accompanying drawing wherein similar reference characters designate similar parts throughout, the improved reamer comprises two opposed semi-cylindrical parts 10 and 11 adapted to be positioned in an encircling arrangement around a drill pipe P. The back of part 10 is equipped with knuckles 12 and 13 and similarly the back of part 11 is provided with knuckles 14 and 15. A cutter pin 16 extends through these knuckles and serves to hingedly connect parts 10 and 11 together at their backs. Between the knuckles the walls of the two parts 10 and 11 are recessed as indicated at 17 and 18. These recesses cooperate to form an opening through the body at the back thereof for affording clearance for the rotatable cutter 19 which is rotatable on cutter pin 16 between washers 20. Part 10 of the body is also provided with top and bottom bosses 21 and 22 through which extends a cutter pin 23 on which is rotatable a cutter 24. This part is formed with an opening 25 therethrough to accommodate the cutter. Similarly, part 11 is equipped with top and bottom bosses 26 and 27, a cutter pin 28, and a cutter 29. The opening in the body for this cutter is indicated at 30. The forward sides of the two parts 10 and 11 are provided with ears indicated at 32 through which draw bolts 33 extend which are tightened by nuts 34 so as to draw the two parts 10 and 11 together into clamping engagement around the drill pipe. Additional ears may be provided as indicated at 32a adapted to receive a locking pin 32b for locking parts 10 and 11 against opening while in the well in the event that draw bolts should break or become unfastened.

I have illustrated the cutter arrangement on the body as having the design embodied in the Vertson patent above-mentioned, wherein the cutter pins are arranged on laterally inclined axis. The cutters 19, 24, and 29 are transversely toothed and are of general barrel-shaped configuration. When the cutter pins and cutters are so arranged the rear cutter pin 16 being laterally inclined forms an inclined hinge at the back 50 of the body and similarly the forward edges on which the ears 32 are located are laterally inclined. It will be understood, however, that the present invention is in no way restricted to the use of laterally inclined cutter pins or cutters but

may be used in conjunction with other cutter arrangements.

Means is provided for preventing rotation of the reamer body relative to the pipe P during 5 reaming. To this end, the reamer body may be equipped as illustrated in Fig. 4. The interior of the top and bottom of the reamer body formed by the two parts 10 and 11 is annularly recessed as indicated at 35, each annular recess receiving one-half of a segmental rubber ring 36. The ring formed by the halves of the rubber ring is made slightly thicker than the depth of the recess so that it will project inwardly and engage the pipe P. Preferably, the interior and exterior 10 surfaces of each ring are knurled or otherwise formed so as to present strong friction surfaces. By means of this construction, when the parts 15 of the body are clamped about the pipe P the rubber ring at the top and bottom of the body will be compressed into firm engagement with the pipe P and with the backs of the recesses forming a strong grip which will resist rotation 20 of the reamer body relative to the pipe.

In Fig. 5 I have illustrated an alternative form 25 of construction for preventing rotation of the body relative to the pipe. As illustrated therein, the top and bottom of the reamer body are recessed as indicated at 38 and 39. These recesses receive the edges of a split metal ring. 30 The interior surfaces of these segmental metal rings indicated at 40 and 41 are knurled so as to tightly grip the drill pipe and the exterior surfaces of these rings are threaded with opposed threads. Inasmuch as the conventional 35 direction of drilling is toward the right, the direction of the thrust imposed upon the body during reaming is in the opposite direction. Consequently, the upper ring 40 has exterior right-hand threads formed thereon and the lower ring 41 has exterior left-hand threads 40 formed thereon. The backs of the recesses 38 and 39 are threaded complementarily thereto. I prefer to have the rings tapered as shown. With this arrangement rotation of the body of the 45 reamer relative to the rings and to the drill pipe merely serves to screw the rings toward the center of the body causing them to tightly grip on the drill pipe and when a sufficient grip has been established further rotation 50 of the body relative to the rings is prevented by the opposed threads. Suitable cap screws 42 may be used for holding the split rings in position until the body has been mounted upon the drill pipe. These cap screws are then removed.

55 Still another manner of preventing rotation of the reamer body relative to the drill pipe is illustrated in Fig. 6. In this construction the top and bottom of the reamer body is recessed with a tapered recess as indicated at 43 to receive the halves of segmental rings 44. These halves of each segmental ring are preferably wedge-shaped in cross-section as shown. The recess 43 is formed eccentrically with respect to the drill pipe P and the segmental ring at the 60 top and at the bottom is similarly formed so as to fit the eccentric recess. The interior surfaces of the rings 44 are knurled so as to grip upon the drill pipe.

When the reamer body is positioned around 65 the drill pipe the halves of the segmental rings are driven into the recesses and may be locked in place such as by set screws 45. As the rings present knurled interior surfaces which grip upon the drill pipe they will not turn relative 70 thereto. As they present eccentric exterior sur-

faces fitting complementary eccentric surfaces at the back of the recess 43, the body fitting around the drill pipe and also these eccentric surfaces cannot rotate relative to the drill pipe.

From the above described construction it will 5 be appreciated that a cheaper reamer construction is provided wherein the amount of material in the body is materially reduced. At the same time the advantages of any preferred reamer design may be retained. The reamer body may 10 be gripped at any desired position on the drill pipe and can be firmly held against rotation relative thereto.

Various changes may be made in the details 15 of the construction without departing from the spirit or scope of the invention as defined by the appended claims.

I claim:

1. A reamer comprising opposed parts adapted to be placed in encircling relationship around a 20 drill pipe, a cutter pin hingedly connecting said parts together, a cutter rotatable upon the cutter pin, and means for preventing rotation of said parts relative to the drill pipe.

2. A reamer comprising opposed body parts 25 adapted to be placed in encircling relationship around a drill pipe, cutter pins mounted upon said parts and laterally inclined with respect to the axis of the drill pipe, one of said cutter pins serving to hingedly connect two adjacent 30 sides of said body parts together, cutters rotatable upon said cutter pins, means for drawing the other two sides of the body parts together, and means for preventing rotation of the body parts relative to the drill pipe.

3. A reamer comprising two body parts hingedly connected together, means for drawing the free ends of the body parts together into clamping engagement with the drill pipe, reamer cutters mounted upon said body parts, means for 40 preventing rotation of the body parts relative to the drill pipe comprising knurled rubber segmental rings recessed in the top and bottom of the body adapted to be compressed between the drill pipe and the body upon tightening the 45 body.

4. A reamer comprising two body parts hingedly connected together, means for drawing the free ends of the body parts together into clamping engagement with the drill pipe, reamer cutters mounted upon said body parts, means for preventing rotation of the body parts relative to the drill pipe comprising segmental rings presenting knurled surfaces engageable with the drill pipe and threadedly engaging the body.

5. A reamer comprising two body parts hingedly connected together, means for drawing the free ends of the body parts together into clamping engagement with the drill pipe, reamer cutters mounted upon said body parts, means for preventing rotation of the body parts relative to the drill pipe comprising segmental rings presenting knurled surfaces engageable with the drill pipe and threadedly engaging the body, the threads on one ring being opposed to the threads 60 on the other.

6. A reamer comprising two body parts hingedly connected together, means for drawing the free ends of the body parts together into clamping engagement with the drill pipe, reamer 70 cutters mounted upon said body parts, means for preventing rotation of the body parts relative to the drill pipe, comprising segmental rings presenting interior knurled surfaces engageable with the drill pipe and exterior surfaces eccentric 75

with respect thereto, said exterior surfaces being engageable with complementary surfaces on the interior of the body parts, the body parts presenting surfaces adapted to engage the drill pipe.

5. 7. A reamer comprising two body parts hingedly connected together, means for drawing the free ends of the body parts together into clamping engagement with the drill pipe, reamer cutters mounted upon said body parts, means for preventing rotation of the body parts relative to the drill pipe, comprising segmental rings presenting interior knurled surfaces engageable with the drill pipe and exterior surfaces eccentric with respect thereto, said exterior surfaces being engageable with complementary surfaces on the interior of the body parts, the body parts presenting surfaces adapted to engage the drill pipe, said rings being wedge-shaped in section.

10. 8. A reamer comprising opposed body parts adapted to be fastened together in encircling arrangement around a drill pipe, each part extending from top to bottom of the reamer and providing supporting means at top and bottom for cutter pins, cutter pins carried by each part, roller cutters rotatable thereon, and means for locking the parts against rotation on the drill pipe.

15. 9. A reamer comprising opposed body parts adapted to be fastened in encircling relation about a drill pipe, a cutter mounted upon each part adjacent the top and bottom thereof, the cutter-supporting means for each cutter being integrally connected. 5

10. 10. A reamer comprising opposed body parts in the form of a segmental sleeve adapted to be fastened together in encircling arrangement about a drill pipe, each part having upper and lower cutter supporting means, cutters supported by the cutter-supporting means, the upper and lower cutter-supporting means being integrally connected. 10

15. 11. A reamer comprising opposed body parts forming a segmental sleeve, means hingedly connecting the segments of the sleeve enabling them to be opened and closed so as to be positioned in encircling arrangement around a drill pipe, means for fastening the swinging ends of the segments of the sleeve together, upper and lower cutter-supporting means carried by each part, cutters supported between the upper and lower cutter-supporting means, the upper cutter-supporting means being rigidly connected to the 20 lower cutter-supporting means independently of the hinge and fastening means. 25

OTTO HAMMER.
